UNITED STATES PATENT OFFICE.

JOHN AUSTIN BEST, OF AUGUSTA, GEORGIA.

FILING APPARATUS.

1,065,106.

Specification of Letters Patent. Patented June 17, 1913.

Application filed July 27, 1912. Serial No. 711,914.

To all whom it may concern:

Be it known that I, JOHN AUSTIN BEST, a citizen of the United States, and a resident of Augusta, in the county of Richmond and State of Georgia, have invented a new and useful Improvement in Filing Apparatus, of which the following is a specification.

My present invention relates generally to filing systems and more particularly to filing systems of that character described and claimed in my application filed December 5, 1911, and serially numbered 664,058.

In my application referred to, the specific improvement resides in cards apertured in order that they may engage the card supporting and holding rod or bar of an index box in a particular manner, although the broad object, as in the present case, involves the provision of index cards having means whereby to selectively engage card holding means in such a manner that the cards may be arranged in a non-alined series wherein a portion of each card is exposed along certain of the edges of the next adjacent card in front thereof. This arrangement is such that facial portions of each card are visible throughout the series, and enables the cards to be distinguished from one another and selected in a short space of time and without fingering over numbers thereof as in the usual indexing systems.

The specific improvement presented by my present invention resides in the provision of cards having means whereby they may be engaged with selected supporting and holding members of a series, whereby the cards may be arranged in a non-alined series for the purpose before mentioned.

With this in mind my invention resides in the details shown in the accompanying drawing, forming part of this specification and in which.

Figure 1 is a transverse vertical section illustrating guide cards for letter folders constructed in accordance with my invention, and, Fig. 2 is a similar view illustrating a modified form of my invention in which the parts are arranged in vertical series.

In the adaptation of my invention to letter files, as illustrated in Fig. 1, I provide a series of card supporting and holding members in the form of rods A, although

in this form I preferably introduce one or more sheet metal ribs B in order to support the lower edge of the letter folders, indicated at C, and prevent the weight of the latter from causing the rods A to sag. In this form of my invention, the cards D constitute guide cards and are provided with means for engaging the supporting and holding members, said means being in the form of lower ends which are cut away to provide enlarged heads d¹ at their lower extremities which are connected thereto by reduced necks d². The cards D are adapted to be located in connection with said holding members by introducing the lower portion of the same flatwise between selected rods A and subsequently turning the card to a position transverse with respect to the rods and with the neck portion d² between the said rods. In this manner the cards may be arranged in non-alined series and projected above the folders E in order to provide spaces for the writing of names or other data.

In Fig. 2 there is shown an index box within which are arranged vertical series of supporting rods B² adjacent opposite sides, these rods being adapted to support cards D² in a non-alined series, as plainly shown, wherein the upper edge portion of each card is exposed above the respective edge of the next adjacent card in front thereof. These cards are provided at opposite sides with heads d³ connected thereto by neck d⁴, and are introduced with the said heads flatwise between selected pairs of rods B² and subsequently turned to the position shown.

Thus from the foregoing, it is to be noted that my present invention constitutes but an extension of the invention idea set forth in my former application before referred to, and serves to illustrate certain of the numerous forms and adaptations of which my invention is susceptible. It is to be further understood that I reserve all other forms and adaptations of my invention as fall within the terms of the claims in my application just referred to, and those appended hereto.

I claim:

1. The combination of a holder having a plurality of spaced supporting members, and cards having extension heads of greater width than the spaces between said mem-

bers, and also having portions connecting said extension heads thereto, said connecting portions being at least as narrow as the spaces between said members.

5 2. The combination of a holder having a plurality of spaced supporting members, and cards having T-shaped extensions at

their lower edges for engagement with a selected pair of said members.

JOHN AUSTIN BEST.
